(57) CLAIM

We claim the ornamental design for a duvet cover, as shown and described.

DESCRIPTION

FIG. 1 is a front side perspective view of the duvet cover. FIG. 2 is an enlarged detail view of FIG. 1.

FIG. 3 is a back side perspective of the duvet cover.

FIG. 4 is an enlarged detail view of FIG. 3,

FIG. 5 is an enlarged detail of an opening at the bottom of the duvet cover. The opening extends in the same manner along the entire bottom of the duvet cover.

The dark broken lines represent the bounds of a detail view and not the bounds of the claimed design.

The light broken lines represent a parquet background that forms no part of the claimed design.
